SLITTING AND PUNCHING ATTACHMENT
FOR PIECE-END SEWING MACHINESWilfred N. Hadley, Springfield, Vt., assignor to
Parks and Woolson Machine Company, Springfield,
Vt., a corporation

Application May 5, 1943, Serial No. 485,724

14 Claims. (Cl. 112—2)

1

This invention relates to sewing machines in general, and in particular to piece-end sewing machines employed in mills and cloth finishing plants for sewing together the adjacent ends of two lengths or cuts of fabric to enable them to be run through processing machines as a substantially continuous web. In the process of shearing the cloth, it is necessary to avoid shearing the seams joining these adjacent ends, as otherwise the two lengths of cloth would come apart, and automatic devices for detecting the approach of the seams to the shearing point and for suspending the shearing while the seams pass this point are frequently employed. Such devices are shown and described in my Patents No. 2,321,481 and No. 2,321,482, granted June 8, 1943, in which the approach of the seam is detected by feeler fingers yieldingly pressing against one surface of the cloth and reaching through the traveling web to complete an electric circuit which actuates the automatic shearing-interrupting devices to suspend the shearing operation until the seam has cleared the shearing point. In an alternative form disclosed in the first of the above patents, a beam of light passes through the web to actuate a photo-electric cell and close the circuit. Provision is made for letting the feelers or the beam of light through the web at the desired moment either by sewing the seam so loosely as to let the ends of the pieces of fabric stand a fraction of an inch apart, or by trimming the ends so that when stitched together such spaces will be left between the ends at intervals in the length of the seam, or alternatively by cutting or punching holes in the web in predetermined spaced relation from the seam, to let the impulse through.

The present invention is immediately concerned with the provision of simple and effective means for cutting or punching these feeler holes in the web, to enable it to actuate the detecting and shearing-suspending devices of the aforesaid applications when the web is run through a cloth shear equipped with these automatic seam-passing devices. For convenience, the present invention is contrived as an adjunct to the common piece-end sewing machine, so that the desired feeler-holes will be cut in the web in predetermined spaced relation lengthwise of the fabric from the seam, in the act of stitching the ends together to form the seam which is to be protected by the action of the automatic seam-passing mechanism.

In its preferred form, the device comprises essentially a knife or other cutting device which

2

is projected through the planes of the two pieces of cloth while they lie one on top of the other on the cloth support of the sewing machine in the act of stitching the seam, the knife or cutting device being forced through the cloth to make a slit or hole therethrough of the desired length or size at the desired distance away from the seam. Preferably, the knife or other cutting device is actuated automatically at predetermined intervals in the length of the seam, to make a plurality of holes at known intervals in the width of the fabric, to locate the holes in the zone of the width of the web which is covered by the feeler, and to offer an opportunity for a plurality of feeler fingers or light beams to get through the plane of the web to insure certainty of detection.

Other objects of the invention, and the manner of their attainment, are as set forth hereinafter.

Illustrated embodiments of the invention are shown in the accompanying drawings in which

Fig. 1 is a front elevation of certain parts of a railway type piece-end sewing machine, showing the device of the invention applied thereto to cut slits in the web adjacent the seam formed by such machine, and showing the knife with its retaining plate removed to show its shape.

Fig. 2 is a side view on line 2—2 of Fig. 1.

Fig. 3 is a vertical section on line 3—3 of Fig. 1.

Fig. 4 is a view of two successive pieces of fabric joined together by a seam, showing the location of the slits.

Fig. 5 is a front view of certain of the parts of a rotary type piece-end sewing machine, showing a slitting device according to the invention applied thereto.

Figs. 6 and 7 are side and top views of the movable arm which carries the knife in Fig. 5.

Fig. 8 is a section on line 8—8 of Fig. 5.

Fig. 9 is a view in section on line 9—9 of Fig. 5.

Fig. 10 is a view similar to Fig. 5 of a rotary type piece-end sewing machine, showing a punching attachment for punching holes in the cloth adjacent the seam.

Fig. 11 is a plan view of certain of the parts of Fig. 10.

The railway type piece-end sewing machine of Fig. 1 is a Dinsmore machine of conventional commercial design apart from the elements added thereto to embody the invention in such machine. Thus, a traveling carriage 1 sliding or rolling on a track comprising spaced and parallel rails 3 carries a motor 5 driving a sewing machine 7 and also driving a train of gearing (not shown) which propels the entire carriage 1 with its parts along rails 3 from left to right,

while the sewing machine is stitching the ends of the cloth together. The pieces of cloth to be joined are as usual laid one on the other with their ends as closely as possible in register with each other, and impaled on pins 9 mounted in blocks fixed on the ends of strips 11 mounted for adjustment lengthwise along a cloth supporting bar 13 extending lengthwise of the tracks 3. As the stitch forming devices including needle 15 form the seam, the usual trimming devices including the shear 17 trim the rearwardly extending edges of the two layers of fabric into exactly flush relation just ahead of the stitching point, during the travel of the carriage across the width of the fabric. Automatic stop means is provided to open a switch stopping motor 5 and thus to stop the driving of carriage 3 and sewing machine 7 after the needle has passed beyond the right-hand selvages of the fabric. This comprises a cam 19 having a frontwardly extending cam surface which deflects from an upright to a frontwardly-inclined position an arm 21 fixed in a hub 23 having a square axial passage fitting the square-section shipper shaft 25 which is operatively connected to throw the motor switch (not shown) into on or off position when rocked respectively in one or the other direction, this sleeve 23 being positioned lengthwise of shipper rod 25 by its connections through rotating sleeve 27 and rigid linkage 29 with a clamp 31 carrying the right-hand strip 11 and adjustably positioned lengthwise of cloth support 13 in accordance with the width of the fabric being stitched, to enable right-hand pin 9 to hold the fabric fully distended.

In accordance with the invention, a cutter in the form of a sharp-pointed and keen-edged knife 33 is affixed by a superposed plate 35 and screw 37, omitted for clarity in Fig. 1 but shown in Fig. 2, to the depending web of an L-shaped bracket 39 of which the short horizontal web is attached by screw 41 to one side of the square head 43 of a member whose shank 45 is held by a nut 47 in angularly fixed relation in a hub 49 on the end of the long arm of a bell crank 51 pivoted at 53 on a bracket 55 fixed by cap screws 57 to the front edge of carriage 1. On the short arm of bell crank 51 is fastened by screws 59 a member 61 which is located in a plane frontwardly of the machine beyond the forward reach of the cam surface on cam 19. In the course of the travel of carriage 1 to the right along rails 3, the lower end of this member 61 engages the bent upper ends of strikers 63 adjustably fixed by their hubs 65 and set screws 67 on the square shipper shaft 25, which engagement rocks the bell crank clockwise to thrust the point of knife 33 through both plies of the fabric resting on the cloth support 13. As this engagement is momentary only, the slits cut in the cloth are on the order of from 1 to 2" in length, and about an inch forward of the line of the seam. The strikers 63 are set lengthwise of shipper shaft 25 in proportion to the width of the fabric so that the holes will be cut at locations about 11" inward from each selvage. Ordinarily, two strikers 63 will be used to perform a corresponding number of cutting operations in the width of the cloth at the locations indicated, but any number of incisions can be made by adding additional strikers 63 as deemed necessary to insure certainty of operation of the feeler. Of course, when the cloth is opened out with both pieces joined by the seam lying in the same plane, the two cutting operations will have formed 4 slits in the cloth, these slits being located in pairs

the members of which are in equally spaced relation from the seam and respectively preceding and following the seam. Thus, if the feeler should fail to detect the slit of such pair which precedes the seam, it still has a chance to make contact through that following the seam, and because the two slits thus located in line with each other warpwise of the cloth are only a couple of inches apart, while the jump of the shearing blades to clear the seam regularly amounts to six or more inches, the actuation of the shearing-suspending mechanism will occur in ample season to save the seam from injury. Pins fixed in web 39 at each side of the shank of knife 33 prevent rotation of the latter about its retaining screw 37.

Fig. 4 is a plan view of two successive pieces 69, 71 of fabric joined together by a butted seam made by a row of stitches 73, showing at 75 the relative location of the slits made by a single operation of knife 33 at the stated interval inward from the left hand selvage and at 77 the corresponding slits near the right hand selvage.

A knife guard is provided to protect the operator's hands from possible injury by the knife 33 when projected up through the cloth in making the slits. For this purpose, a presser 72 is affixed to the motor shelf 74, extending downwardly nearly to the level of cloth rest 13 and thence forwardly over the cloth when supported on such rest, to a point forward of the knife's location. A slot is cut in the member 72 to permit the knife to pass through the horizontal forwardly-extending portion thereof, and a small hood 76 identical with that shown at 131 in Figs. 5 and 8 is affixed to the top surface of this portion to cover the point of the knife when elevated. To facilitate applying the cloth to the cloth support 13, this presser 72 is formed in two parts hinged together along line 78, being held down in working position to resist the upward thrust of the knife or alternatively in lifted position with its horizontal edge tipped up against motor 5 by a contracting spring 80 hitched to one edge of the swinging portion and anchored to the under side of motor shelf 72.

As rockshaft 25 stays in the angular position given it by arm 21 after the knock-off cam 19 has deflected the arm to stop the machine, strikers 63 are out of the path of member 61 while the carriage is being pushed back to the left-hand end of the machine in preparation for a new seaming and slitting operation.

In Figs. 5 to 9 is shown the application of the same slitting method to a Dinsmore rotary type piece-end sewing machine of conventional type, of which, as in the case of the railway type sewing machine, only those parts immediately concerned with the invention are shown. In this case, the body of the sewing machine, which usually corresponds to that shown at 7 in Fig. 1, is indicated at 79 mounted on a shelf 81 on the pedestal (not shown) of the machine, which pedestal also supports a shaft 83 on which is mounted a broad-rimmed wheel 85 serving as a cloth rest. Pins 87 are fixed in pairs in spaced relation about the rim of this cloth support, on which the ends of the two pieces of cloth to be joined are impaled in widthwise-stretched and superposed relation with their extremities in approximate register with each other and in position to pass under the presser-foot and needle 89 of the sewing machine as the wheel revolves. As before a trimmer (not shown) cuts off the ends of the two pieces of cloth flush with each other just ahead of the stitching point defined by needle 89, the wheel 85 revolving

to carry the cloth past the needle until a seam extending across the full width of the fabric has been completed.

In accordance with the invention, a bracket 91 is fixed to the shelf 81, and extends forward into proximity with the rim of wheel 85, where there is a member having a base 93 attached by screws 95. On this base is an integral sleeve 97, in which is fixed a pin 99 forming the pivot for one end of a knife carrier 101 having a hub 103 fitting the pin 99 and retained thereon by the head of such pin. The left hand extremity (Fig. 5) of this knife carrier is offset rearwardly away from wheel 85 and formed with a hub 105 in which is fixed a pin similar to that indicated at 43, 45 in Fig. 2. To the enlarged head 107 of this pin there is attached by screw 109 the short horizontal portion of an L-shaped bracket 111 corresponding to the part 39 of Fig. 2. On the long vertical portion of bracket 111 is mounted a knife 113 made and attached as in Figs. 1 and 2, by means of a plate 115 and screw 117 and pins 119.

The intermediate portion of knife carrier 101 is made with considerable depth, and is provided with a transversely extending slot 121, in which is adjustably fixed a stud 123 having a reduced end portion 125 extending under the rim of wheel 85, where it is engaged at periodic intervals in the revolution of the wheel incident to the feeding of the cloth past the needle 89, by a cam which swings the knife carrier clockwise about its pivot 99 to force the pointed end of knife 113 up through both thicknesses of the cloth closely adjacent the rear edge of the rim to form the feeler slits in the cloth. The needle passes through the cloth at a point 153 about $\frac{3}{4}$ " to the rear of the rim of the cloth supporting wheel. The cam which actuates the knife is indicated at 127, and has the shape in side elevation shown in Fig. 5. It is attached by means of its shank and screws 129 to a generally T-shaped bracket 131 which is attached by screws 133 to the interior surface of the rim of wheel 85. As in the case of Fig. 1 the slits are commonly formed about 11" in from each selvage of the fabric, and therefore two cams, each on its bracket, are provided in the circuit of wheel 85, in proper spaced relation about the wheel to suit the width of the fabric being seamed. A plurality of threaded holes (not shown) is provided along the rim of wheel 85, to provide for appropriate shift of one bracket with its cam to suit the width of the cloth.

As before in Fig. 1, a presser 135 and guard 137 for knife 113 are provided above the cloth, the presser here comprising a strip of metal curved to conform to the periphery of wheel 85, with both ends bent up and the right hand end welded to the square head 139 of a pin having a shank 141 rotating freely in a hub 143 on the end of a lug 145 formed integrally with hub 97 and base 93 therefor. Thus lug 145 is rigid with base 93, and is merely a bracket. Collar 147 retains pin 141 in hub 143. This presser 135 is slotted directly above the knife, and the slot is covered by the guard 137 fixed to the presser 135, just as in Fig. 1. Any suitable spring means is used to hold presser 135 firmly enough against the cloth to insure penetration by the knife. A portion of the width of presser 135 presses against the cloth where the latter is supported on the rim of cloth supporting wheel 85. The two plies of cloth are indicated at 151 in Figs. 8 and 9, the cross indicated at 153 denoting the line along which the needle penetrates the fabric.

Another alternative form of the invention is

shown in Figs. 10 and 11, in which devices are provided on a conventional Densmore rotary type piece-end sewing machine for cutting or punching round holes at the same general locations in the fabric and for the same purposes as the slits 75 previously described. In this embodiment, the parts of the sewing machine are or may be as usual in these conventional machines and as shown and described in connection with Fig. 5, except for the elements added to embody the invention therein, and bear the same reference characters as in Fig. 5, except that the usual trimmer, not shown in Fig. 5, is indicated at 155.

In accordance with the invention, a pair of tubular punching elements 157 is fixed in the rim of wheel 85 with the two members of the pair in closely spaced relation in the direction around the rim, there being at least two pairs thus located at proper angular intervals about the rim to form a pair of holes through both plies of the fabric during the stitching operation at points roughly 11" in from each selvage. The exterior of each punching element is screw threaded and screwed into a threaded hole through the rim until their cutting ends extend above the surface of the rim far enough to insure cutting through both plies of the thickest fabric to be stitched, the elements being fixed in this relation by lock nuts 159. The elements 157 are tubular and are made of extra hard alloy steel and provided with keen cutting edges. An ample series of threaded holes additional to those occupied by the four punching elements are provided in the rim, to enable shift of the punches to suit the particular width of the fabric.

Cooperating with the punches is a bronze roll 161 which rolls on the surface of the upper ply of the fabric stretched around the rim of wheel 85 and impaled on pins 87 during the stitching, the roll rolling between the pairs of pins as shown in Fig. 11 and over the cutting ends of the punches to force the latter through both plies of the fabric, thereby making clean-cut holes through the fabric normally of about $\frac{1}{4}$ " in diameter, through which the feeler fingers make sure contact with the platen of the feeler device, or the beam of light shines to actuate the photo-electric cell, to suspend the shearing while the seam passes the shearing blades. This roll rotates on a pin 163 fixed in the end of arm 165 pivoting on a pin 167 fixed in lugs 169 on a base 171 fastened to a lateral extension of the shelf 81 which supports the sewing machine 79. A heavy contracting spiral spring 173 is anchored at its lower end to the pedestal (not shown) supporting the sewing machine, and is connected by link 175 with the pin 163 to force the roller against the cloth with the requisite pressure to cause the punches to cut through the latter as the revolution of wheel 85 during the stitching carries the punches and the superposed cloth past the roll.

The adaptation of the slitting and punching attachments to other types of piece-end sewing machines beside those shown and described herein, is performed in analogous manner, as will be apparent to those skilled in the art.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but

What I do claim is:

1. A sewing machine for joining cut ends of cloth having in combination stitch-forming devices, a wheel supporting the cloth during the sewing and rotating to carry the cloth past the stitching-forming devices, a cutter, and means forcing the cutter through the cloth on the opposite side of the seam from the cut ends while the cloth is being carried by the wheel.

2. In a cloth-sewing machine, in combination, stitch-forming devices, a support therefor, a cloth support, means effecting relative movement of the two supports to feed the cloth past the stitch-forming devices, a punch mounted on one of these supports, and means in connection with the other of these supports cooperating with the punch to force the latter to cut through the threads of the cloth.

3. A sewing machine for joining cut ends of cloth having in combination stitch-forming devices, a wheel supporting the cloth during the sewing and rotating to carry the cloth past the stitch-forming devices, at least one punch rotating with the wheel, and means pressing the cloth against the punch to cause the latter to cut through the cloth.

4. A sewing machine for joining cut ends of cloth having in combination stitch-forming devices, a wheel supporting the cloth during the sewing and rotating to carry the cloth past the stitch-forming devices, a punch fixed in the cloth-supporting surface of the wheel, and a roller rolling on the surface of the cloth where the latter is supported by the wheel, such roller pressing the cloth against the punch to cause the latter to cut through the cloth.

5. A sewing machine for joining cut ends of cloth having in combination a track, a carriage traveling along such track, a sewing machine on the carriage, a cutter movably mounted on the carriage, and means thrusting the cutter through the cloth on the opposite side of the seam from the cut ends of the cloth.

6. A cloth-sewing machine having in combination a track, a carriage traveling along such track, a sewing machine on the carriage, a cutter movably mounted on the carriage, and means in operatively fixed relation with respect to the track actuating the cutter through movement of the carriage and cutter past such means to thrust the cutter through the cloth.

7. In a cloth-sewing machine, in combination, stitch-forming devices, a support therefor, a knife movably mounted on such support, a cloth support, and cam means in connection with the cloth support actuating the knife, through relative movement of the two supports, to thrust the knife through the cloth to cut holes in the latter.

8. In a cloth-sewing machine, in combination, stitch-forming devices, a support therefor, a cloth support, means effecting relative movement of the two supports to feed the cloth past the stitch-forming devices, a knife mounted on one of these supports, and cam means in connection with the other of these supports actuating the knife through the said relative movement to thrust the knife through the cloth to cut holes in the latter.

9. A cloth-sewing machine having in combination a track, a carriage traveling along such track, a sewing machine on the carriage, a knife pivotally mounted on the carriage, and knife-actuating members alongside the path of the

carriage at one or more points in the length of the carriage's travel swinging the knife about its pivot to thrust it through the cloth to cut holes in the latter beside the line of stitches formed by the sewing machine.

10. A sewing machine for joining cut ends of cloth having in combination a track, a carriage traveling along such track, a sewing machine on the carriage, a knife pivotally mounted on the carriage, power means for driving the carriage and the sewing machine, a rockshaft extending along the track controlling the power driving means, and strikers adjustably fixed on such rockshaft each swinging the knife on its pivotal mounting as the knife travels along the track, whereby the knife is thrust through the cloth to cut holes in the cloth.

11. A sewing machine for joining cut ends of cloth having in combination stitch-forming devices, a wheel supporting the cloth during the sewing and rotating to carry the cloth past the stitch-forming devices, a pivotally mounted knife, and means on the wheel swinging the knife on its pivot to thrust the knife through the cloth to cut holes in the latter.

12. A sewing machine for joining cut ends of cloth having in combination a fixed support, stitch-forming devices on such support, a traveling support carrying the cloth past the stitch-forming devices, a knife pivotally mounted on one support, and a striker on the other support engaging a part in connection with the knife in passing, such engagement swinging the knife about its pivot and thrusting the knife through the cloth to cut holes in the latter.

13. A sewing machine for joining cut ends of cloth having in combination a support, stitch-forming devices on such support, a wheel supporting the cloth during the sewing and rotating to carry the cloth past the stitch-forming devices, an arm pivotally mounted on the support, a knife mounted on the arm, and a cam on the wheel engaging and moving the arm as the wheel rotates, thereby thrusting the knife through the cloth to cut holes in the latter.

14. A sewing machine for joining cut ends of cloth having in combination a support, stitch-forming devices on such support, a wheel supporting the cloth during the sewing and rotating to carry the cloth past the stitch-forming devices, an arm pivotally mounted on the support, a knife mounted on the arm, a cam on the wheel engaging and moving the arm as the wheel rotates, thereby thrusting the knife through the cloth to cut holes in the latter, and a presser holding the cloth against displacement under the thrust of the knife.
